UNITED STATES PATENT OFFICE

169,588

SCARF

Willy Hanselmann, Paris, France, assignor to Edgar C. Hyman Co. Inc., New York, N. Y., a corporation of New York

Application December 10, 1952, Serial No. 22,612

Term of patent 7 years

(Cl. D3—12)

To all whom it may concern:

Be it known that I, Willy Hanselmann, a citizen of the Federal Republic of Switzerland, and a resident of Paris, France, have invented a new, original, and ornamental Design for a Scarf, of which the following is a specification, reference being had to the accompanying drawing, forming a part hereof.

The figure is a plan view of a scarf showing my design.

I claim:

The ornamental design for a scarf, substantially as shown.

WILLY HANSELmann.
